(57) **CLAIM**

The ornamental design for a shotgun shell pouch, as shown and described.

DESCRIPTION

FIG. 1 is a front, left side, and top perspective view of a shotgun shell pouch showing my new design, where a rotatable belt clip of the shotgun shell pouch is shown in an upright position. A rectangular shotgun shell box is shown in dash-dot-dot broken lines and is not part of the design; FIG. 2 is a rear, right side, and top perspective view of the shotgun shell pouch of FIG. 1, showing the rotatable belt clip of the shotgun shell pouch in the upright position; FIG. 3 is a front, left side, and bottom perspective view of the shotgun shell pouch of FIG. 1; FIG. 4 is a front elevation view of the shotgun shell pouch of FIG. 1; FIG. 5 is a rear elevation view of the shotgun shell pouch of FIG. 1; FIG. 6 is a left side view of the shotgun shell pouch of FIG. 1; FIG. 7 is a right side view of the shotgun shell pouch of FIG. 1; FIG. 8 is a top plan view of the shotgun shell pouch of FIG. 1; FIG. 9 is a bottom plan view of the shotgun shell pouch of FIG. 1; and, FIG. 10 is another rear, right side, and top perspective view of the shotgun shell pouch of FIG. 1, showing the rotatable belt clip of the shotgun shell pouch rotated about **180** degrees from the upright position shown in FIG. 2. The broken lines in the drawings illustrate portions of the shotgun shell pouch that form no part of the claimed design.
